UNITED STATES PATENT OFFICE.

RICHARD C. LEAKE, OF ROCHESTER, NEW YORK, ASSIGNOR TO GENERAL RAILWAY SIGNAL COMPANY, OF GATES, NEW YORK, A CORPORATION OF NEW YORK.

SELECTIVE SIGNALING SYSTEM.

1,209,598.

Specification of Letters Patent. Patented Dec. 19, 1916.

Application filed December 11, 1914. Serial No. 878,696.

To all whom it may concern:

Be it known that I, RICHARD C. LEAKE, a citizen of the United States, and a resident of the city of Rochester, in the county of Monroe and State of New York, have invented a new and useful Improved Selective Signaling System, of which the following is a specification.

This invention relates to an improved selective signaling system, and particularly to such a system in which a distinctive answer back indication is given to the operator at a central station, who has caused the movement of a signal at a remote point, that the signal has actually assumed the position intended.

The primary object of this invention is to inform the operator of a selective signaling system by means of a preliminary indication, of the characteristic answer back indication which is to be received by him due to the changing by him of the position of a remote control device.

Other objects and advantages will appear as the description of the invention progresses, and the novel features of the invention will be particularly pointed out in the appended claims.

In describing the invention in detail, reference is had to the accompanying drawing, wherein I have illustrated a preferred physical embodiment of my invention, and in which the figure illustrates schematically a preferred arrangement whereby the invention may be practised.

As is well known to those skilled in the art, selective signaling systems are old and well known which comprise a series of signals located at points remote one from the other, and from a central point, each of which signals is selectively controlled from the said central point over two line wires, and which have associated with each signal a device automatically operated by the changing of the position of the signal which causes what is known as an "answer back indication", to be sent back over the line wires upon a changing of position of the signal to notify the operator at the central point that the signal which he intended to operate did actually operate, and did actually assume the position intended. These systems which are old in the art, also in general include devices known as "individual calling keys", located at the central point, which are so arranged and construct-

ed that an operation of any one calling key causes an operation of a particular signal. Such calling keys are typified by that shown in the patent to Maurice F. Geer and Richard C. Leake, dated August 4, 1914, No. 1,105,766. These keys consist in general of a handle which is twisted or turned by an operator, and of mechanism which then automatically returns the handle to its original position, and at the same time revolves certain disks having circuit making teeth in their periphery, as fully shown and described in the patent above referred to.

As each key is individual to each signal, and each signal gives a characteristic answer back, applicant has taken advantage of such fact by causing the operation of each key to produce, before the key has entirely completed its movement, and before the signal governed by the key has actually completed its change of position and generated its characteristic answer back, to itself generate the same characteristic answer back as that which will almost immediately thereafter be generated by the signal itself, so as to thereby inform the operator as to the particular answer back which he must obtain.

On account of the fact that each signal generates a different answer back indication and there are often, under the control of the despatcher, a large number of signals it cannot be expected that an operator will be able to remember the various answer back indications he should receive as a result of operating each individual calling key and it seems very likely that an operator would, sooner or later, make a mistake by accepting a wrong answer back indication. The applicant has in the invention herein described furnished a means which prevents any possibility of the operator making such an error due to faulty memory by causing a characteristic preliminary indication, when the calling key is operated, which is of exactly the same code as the answer back indication which he should receive immediately thereafter upon the proper operation of the signal.

In order to illustrate the invention applicant has not shown any particular type of selector or signal or answer back device, as the manner of construction and mode of operation of such is immaterial to his invention, but has merely shown diagrammati-

cally a pair of line wires which in practice are carried throughout the system, a selector and an answer back mechanism connected across said line wires and a signal governed by said selector and controlling said answer back mechanism. Neither is the particular type of individual key material to applicant's invention, and consequently applicant has illustrated in a schematic way a key which when practically formed may be considered similar to that shown and described in the patent above referred to.

In the drawing the wires 1 and 2 designate the ordinary and well known line wires which extend from a central or operator's station to the various signal stations as described.

As is usual, the telephone receiver 3 is connected in bridge of the line wires 1 and 2 because, as is well known to those skilled in the selective signaling art, the line wires 1 and 2 by which current flows to govern the selectors, is also used as the telephone circuit by which communication is had between the central station and the various signal stations.

In the drawing the selector, answer back mechanism and signal hereinbefore referred to which are located at one station are shown diagrammatically. The selector S is bridged across the line wires 1 and 2 by wires 59 and 60 and is arranged to control the answer back mechanism A B by circuits illustrated schematically as comprising two wires 61 and 62. The selector S also controls the signal E by circuits which are shown as comprising wires 61, 62, 63 and 64; and the answer back mechanism A B in turn is governed by the signal S by circuits represented by the wires 63 and 64. The answer back mechanism A B is bridged across the line wires 1 and 2 by the wires 65 and 66. It should be clearly understood that no particular construction of the selector S, answer back mechanism A B or the signal E is necessary for use with this invention, and any construction or arrangement of these parts will be sufficient which is suitable for enabling the operator at the central station to control the positions of the signal E and which causes answer back indications of the position of the signal E to be sent to the central station. One arrangement and construction of these parts is disclosed in the Signal Engineer on page 213 and the following pages of the July 1914 issue.

The means shown for transmitting selective impulses to the line wires 1 and 2 for operating the selector S is illustrated by means of the conventional disks A, B and C, which, as actually constructed, may be of the form illustrated in the patent above referred to, and numbered therein as 59, 63 and 61. As is usual in selective signaling systems, the rather high potential battery

13 does not have its current broken by means of the disks A, B and C, but is broken by means of the pole changing switch S, which is controlled by the polarized relay T, which is in turn controlled by the disks A, B and C. The impedances 8, 9, 10 and 11 and the condensers 7 and 12 are the ordinary and well known expedients to prevent undesired interference with the telephone receiver 3.

As fully shown and described in the patent hereinbefore referred to, the disk A has teeth 17 thereon, three in number, which upon rotation of the disk A, contact with the spring 14, and so cause one coil of the polarized relay T to be alternately energized and deenergized by a circuit which may be traced as follows: one terminal of the battery 21, wires 22 and 23, disk A, teeth 17, spring 14, extension 14' of spring 14, wire 24, coil 25 of polarized relay T, and wires 26 and 27 to the other terminal of the battery 21. Current flowing in the above traced path causes the right hand end of armature 58 to be raised, and so causes the arm attached to said armature to move the conducting arms 29 and 30 to the left from their mid-position, as shown, so that they connect with the wires 33 and 31 respectively, thereby allowing current to flow from the battery 13 to the line wires 1 and 2.

As fully shown and described in the patent above referred to, after the teeth 17 have finished contacting with spring 14, the teeth 18 on disk B begin to make and break contact with spring 15, and thus cause an alternate energization and deenergization of the coil 28 of polarized relay T, so that current flows through said coil in a path as follows: one terminal of the battery 21, wires 22, 38 and 43, disk B, teeth 18, spring 15, wire 41, 105 coil 28 and wires 42 and 27 to the other terminal of the battery 21. Current flowing in the above traced path causes the left hand end of armature 58 to be raised and thereby causes the arm attached thereto to move the 110 conducting arms 29 and 30 to the right of their mid-position, as shown in the figure, into contact with wires 31 and 32 respectively, thereby allowing current to flow from the battery 13 to the line wires 1 and 2, but 115 in a reverse direction from that caused by the movement of the conducting arms 29 and 30, to the left of their mid-position, as shown.

In order to show an individual calling key similar in all respects to that shown and described in the patent above referred to, applicant has also included the disk C in the figure, which has one tooth 19 on its periphery, which, as fully described in the patent above referred to, makes contact with the same spring 14 that the teeth on the disk A make contact with, but shown in the figure of the drawing as two separate springs for greater clarity. The tooth 19 130

on the disk C makes contact with spring 14 after the teeth 18 on the disk B have finished making contact with the spring 15. The contact of tooth 19 and spring 14 causes an energization of the coil 25 of the polarized relay T by establishing a circuit which may be traced as follows: one terminal of battery 21, wires 22, 38, 39 and 44, disk C, tooth 19, spring 14, wire 24, coil 25, wires 26 and 27 to the other terminal of the battery 21. Such an energization of coil 25 causes the right hand end of armature 58 to be raised and the arm attached thereto to move the conducting arms 29 and 30 to the left of their mid-position, as shown on the figure so that they contact with wires 33 and 31 respectively, thereby allowing current to flow from the battery 18 to the line wires 1 and 2 in the same direction that it was caused to flow by the contact of the teeth 17 of disk A with the spring 14, thereby finishing the sending of those impulses to the line wires 1 and 2 necessary to operate a selector of the type mentioned and schematically illustrated in the patent hereinbefore referred to.

All of the devices hereinbefore described and explained are old and well known in the art, and contain no features of novelty at-tempted to be covered by this application.

To the same shaft 57 to which the disks A, B and C are rigidly attached, is also rigidly attached a disk D, which consequently must revolve in synchronism with the other disks, and must complete its rotation simultaneously with the completion of the rotation of the other disks A, B and C, so that, as will be well understood by those skilled in the art of selective signaling, it must complete its movement before a semaphore signal E controlled by a selector S, such as is schematically shown in the patent hereinbefore referred to, has assumed a new position due to the operation of such selector S, and consequently before such signal E can have returned an answer back indication over the line wires 1 and 2 to the telephone 3 at the central station. The rotation of disk D causes the teeth 20 on the periphery thereof to engage with the spring 16, thus alternately breaking and making a circuit which may be traced as follows: one terminal of the battery 21, wires 22, 38, 39 and 40, disk D, teeth 20, spring 16, wire 45, contact point 46, spring biased armature 47, primary of an induction coil 48, and wires 50 and 27 to the other terminal of the battery 21. Current flowing in the above traced path causes, as is well understood by those skilled in the electrical art, the rapid vibration of armature 47, so that an alternating current is thereby produced in the secondary coil 49, which, by means of wires 51 and 52 through the condensers 53 and 54 and wires 55 and 56, is transmitted to wires 37 and 34,

which are directly connected, through the reactance coils 9 and 8 to the wires 36 and 35, which connect through wires 6, 5, 4, and condenser 7 to the telephone receiver 3. The alternating current generated in the secondary coil 49 is transmitted by the connection above described, to the telephone receiver, thereby causing an operation thereof in the nature of audible clicks, as many in number as there are teeth on the disk D, so that there is produced upon the ear of a listener at receiver 3 a characteristic series of sounds.

In the practice of applicant's invention, although there may be, and probably will be, a large number of signals to be controlled, there will be a key individual to each signal for the control of that signal only. Attached to the shaft bearing the impulse disks of each key will be a disk having teeth formed in its periphery of such number, and in such spaced relation as will generate in a receiver as 3 the same code impulses or audible clicks as will be produced by the particular signal governed by that key in generating an answer back set of impulses for notifying the operator at the central station that the signal has actually assumed the position intended.

Most of the answer back mechanisms act by sending to the central station a series of direct current impulses. Such impulses, acting upon a telephone receiver, cause a peculiar tone of click which can be easily recognized by one at all expert as being caused by a direct current. It is advisable to have the tone of the clicks produced in the receiver by the preliminary indication caused by the rotation of the calling key different from the tone of the clicks produced by the answer back mechanism. Applicant has accomplished this object by making use of the induction coil having the primary 48 and the secondary 49. That is, instead of sending a series of direct current impulses to the line wires 1 and 2 to produce a preliminary indication by the rotation of the disk D, these impulses are caused to flow through the primary of an induction coil, thereby producing in the secondary of that coil an alternating current which is then caused to affect the telephone receiver 3. The tone of the clicks thus generated in the receiver 3 are distinctively different from the tone of the clicks produced in the receiver 3 by the direct current impulses transmitted to the line wires by the answer back device itself. This expedient obviates any difficulty which might arise if the operator could not clearly distinguish the preliminary indication from the actual indication which he is to receive later.

Although I have particularly described the construction of one physical embodiment of my invention, and explained the opera-

tion and principle thereof; nevertheless, I desire to have it understood that the form selected is merely illustrative, but does not exhaust the possible physical embodiments 5 of the idea of means underlying my invention.

What I claim as new and desire to secure by Letters Patent of the United States, is:

1. In a selective signaling system, in combination: a remote control device; means for controlling said remote control device from a central station; means controlled by said remote control device for giving a code indication at the central station of the movements of said remote control device; and means operated by said first mentioned means for giving preliminarily at the central station, the same code indication distinctive from the indication given by the means controlled by said remote control device.

2. In a selective signaling system, in combination: a remote control device; means for controlling said remote control device from a central station; a pair of line wires; a telephone receiver bridged across said line wires and adapted to receive indications from said line wires; means controlled by said remote control device for sending a code indication over said line wires to the telephone receiver for each movement of said device; and means operated by said first mentioned means for giving preliminarily at the central station an indication of the same code as the first mentioned indication but of a different tone.

3. In a selective signaling system, in combination: a remote control device; a selector for controlling said remote control device; an impulse transmitter for controlling said selector from a central station; a pair of line wires; means controlled by said remote control device for giving a code indication over said line wires at the central station, of the movements of the remote control device; and means operated by said impulse transmitter for giving preliminarily at the central station an indication of the same code over said line wires, distinctive from the indication given by the means controlled by said remote control device.

4. In a selective signaling system, in combination: a remote control device; a selector for controlling said remote control device; an impulse transmitter for controlling said selector from a central station; a pair of line wires; means controlled by said remote control device for giving over said line wires to the central station, a code indication of the movements of the said remote control device; vibrating means for giving

preliminarily at the central station the same code indication distinctive from the indication given by the means controlled by said remote control device; means governed by said impulse transmitter for operating said vibrating means subsequent to the operation of said impulse transmitter; and a telephone receiver bridged across said line wires for receiving said indications.

5. In a signaling system, in combination: two line wires; a telephone receiver bridged across said line wires; a remote control device; means governed by said remote control device for sending over said line wires to a central station a code indication of the operated condition of said device; a selector for governing said remote control device; a calling key for controlling said selector; means operated by said calling key for applying to said line wires impulses in the same code as said indication; and means for modifying the electrical character of said impulses, whereby said impulses can be distinguished from the indication given by the means governed by said remote control device.

6. In a signaling system, in combination: a remote control device; a selector for controlling said device; a pair of line wires; a telephone receiver bridged across said line wires; a source of energy; an impulse transmitter for governing the connection between said source of energy and said line wires and governing said selector by the impulses sent over said line wires; answer back mechanism controlled by said remote control device for sending code indications over said line wires indicating the movements of said remote control device; a local circuit at the central station connected to said line wires; means governed by said impulse transmitter for applying to said local circuit a preliminary indication of the same code as that sent by said last mentioned means; and an induction coil included in said local circuit for modifying the current therein, whereby said preliminary indication is distinctive in tone from the indication sent by said answer back mechanism.

7. In a selective signaling system, in combination: two independent means for sending the same code indication distinctive in tone over the same line wires to a common receiving point; and means for governing said means to cause one of said indications to be received preliminarily to the other.

RICHARD C. LEAKE.
